US00D983603S

(12) **United States Design Patent** (10) Patent No.: **US D983,603 S**
Shi et al. (45) Date of Patent: **** Apr. 18, 2023**

(54) **BLADE FOR A MICRO PUREE MACHINE**

(71) Applicant: **SharkNinja Operating LLC**, Needham, MA (US)

(72) Inventors: **Ming Li Shi**, Dong Guan (CN); **Xu Sheng Deng**, HuiZhou (CN); **Pushan He**, Shenzhen (CN); **Ping Chu**, Kowloon (HK)

(73) Assignee: **SHARKNINJA OPERATING LLC**, Needham, MA (US)

(**) Term: **15 Years**

(21) Appl. No.: **29/814,197**

(22) Filed: **Nov. 4, 2021**

Related U.S. Application Data

(63) Continuation-in-part of application No. 17/139,567, filed on Dec. 31, 2020.

(57) **CLAIM**

The ornamental design for a blade for a micro puree machine, as shown and described.

DESCRIPTION

FIG. 1 is a top/front/left side perspective view of a blade for a micro puree machine, showing our new design;

FIG. 2 is a bottom/rear/right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings depict portions of the blade that form no part of the claimed design.
